CLAIM

The ornamental design for a wind generator, as shown and described.

DESCRIPTION

FIG. 1 is a front perspective view of a wind generator showing our new design;

FIG. 2 is a front perspective view thereof in an extended position;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken line elements shown in FIGS. 3, 4, and 8 represent unclaimed subject matter and form no part of the claim.
